UNITED STATES PATENT OFFICE

102,575

DESIGN FOR A SPRAYING APPARATUS CASING

Frank W. Ofeldt, McKeesport, Pa., assignor to Homestead Valve Manufacturing Company,
Coraopolis, Pa., a corporation of Pennsylvania

Application June 29, 1936, Serial No. 63,562

Term of patent 14 years

To all whom it may concern:

Be it known that I, Frank W. Ofeldt, a citizen of the United States of America, residing at Mc-Keesport, in the county of Allegheny and State of Pennsylvania, have invented a new, original,
and ornamental Design for a Spraying Apparatus Casing, of which the following is a specification, reference being had to the accompanying drawing, forming part thereof.

The figure is a perspective view of a spraying apparatus casing showing my new design.

The other side of the casing is substantially the same as the side shown.

I claim:—

The ornamental design for a spraying apparatus casing, as shown and described.

FRANK W. OFELDT.
